Primary Examiner — Joseph Kukella*Assistant Examiner* — Arva P Adams*(74) Attorney, Agent, or Firm* — Larry K. Roberts(57) **CLAIM**

The ornamental design for a tumbler with lid as shown and described.

DESCRIPTION

FIG. 1 is an isometric view of a tumbler with lid showing the new design;

FIG. 2 is a back elevation view thereof;

FIG. 3 is a front elevation view thereof;

FIG. 4 is a top view thereof;

FIG. 5 is a bottom view thereof;

FIG. 6 is a right side elevation view thereof; and,

FIG. 7 is a left side elevation view.

The features shown on the drawing in broken lines are for illustrative purposes only and are not a part of the scope of the claim of the embodiment in which they are shown.
